LAMP HOLDER FOR CIRCULAR TUBULAR LAMPS

John M. Pistey, Fairfield, Conn., and Frank C. De Reamer, Lake Worth, Fla., assignors to General Electric Company, a corporation of New York

Application April 15, 1946, Serial No. 662,128

9 Claims. (Cl. 240—51.12)

1

Our invention relates to lamp holders and more particularly to lamp holders for circular tubular discharge lamps, for example, circular fluorescent lamps of the type now coming on the market.

Circular fluorescent lamps are generally provided with a contact base at one place in the periphery of the lamp tube. The contact base is usually formed as a tube and has radially extending contact pins whereby electrical connections are made to the lamp electrodes. Such lamps are preferably supported at two points at least. Since electrical connection must be made to the lamp base, the latter naturally indicates one point for the lamp support; the other point or points of support may be spaced around the loop of the lamp.

The structure of the connecting support must be such that adequate electrical contact with the lamp pins is made at all times and even though the lengths of the pins may vary due to manufacturing tolerances. Mechanically, the support structure must securely hold the lamp, even under vibration conditions, while at the same time providing for easy lamp replacement. Moreover, in order to provide adaptability to a wide variety of uses, the elements of a complete lampholder should be decorative as well as utilitarian and should interfere as little as possible with the light produced by the circular lamp.

Accordingly, a primary object of our invention is the provision of an improved construction of a lamp holder fixture for circular lamps which shall satisfy the foregoing requirements and which includes elements adapted for use in various fixture arrangements and particularly adapted for use with fixture arms such as form parts of floor lamps, table lamps, or the like. A further object of our invention is the provision of an improved lampholder or contact receptacle element for aiding in the support of a circular fluorescent lamp and for making contact with the lamp base. A still further object of our invention is the provision of improved support elements for a circular fluorescent lamp.

In carrying out our invention we provide a lampholder fixture having a plurality of arms extending outwardly from a base and terminating in a circle. Lamp supporting and contacting elements are mounted at the ends of these arms and are similarly shaped and designed to engage small portions only of the lamp tube. The lampholder proper, or contact receptacle, or socket element, as it is variously called, is constructed so that it may be mounted on a fixture

2

arm or the like and is provided with contact members having freely floating, spring biased contact elements therein. The lamp supporting elements which are not required to provide for electrical connection, generally described as "supports" or "tension supports," are also constructed for mounting on a fixture arm or the like; these supports include a spring tensioned, pivotally mounted clamp element which is adapted to engage the lamp tube.

In the accompanying drawing, Fig. 1 is a plan view of a circular fluorescent lamp mounted on a lamp holder constructed in accordance with our invention; Fig. 2 is a view of the holder in elevation; Fig. 3 is a partial sectional view of the holder taken along the line 3—3 of Fig. 1; Fig. 4 is a view of another part of our holder taken along the line 4—4 of Fig. 1, and Fig. 5 is an enlarged view in section of the receptacle contact structure.

Referring to the drawing, our lamp holder is provided with spaced supports 1 for engaging the wall of a circular fluorescent lamp and a contact receptacle 2 supporting and making an electrical connection with the base of the lamp. The supports 1 and receptacle 2 are each mounted on a tubular fixture arm 3 forming part of a table lamp 4. In the particular form of table lamp illustrated, three fixture arms are employed but it should be manifest that the number of arms may be increased or decreased at will depending upon the type of lamp with which our holder is used. We have illustrated only one form of the many forms of table or floor lamps with which our invention may be used. It should be noted, however, that the circular fluorescent lamp is preferably supported on at least two points which means that a contact receptacle 2 is used to support the base and one other support 1 to engage and support the loop of the lamp.

Turning now to the construction of the contact receptacle 2 and referring to Fig. 3, the receptacle includes a base 5 formed of any suitable insulating material such as a molded plastic. Base 5 is formed with a curved surface 6 which fits around and closely engages the contact base 7 of the circular fluorescent lamp. It should be noted that the lamp base is formed as a tube to provide a continuation of the lamp tube and that the lamp contact pins extend radially from the base. A portion of the curved surface of the receptacle is provided with a raised projection 8 which fits into a recess 9 in the lamp base and assists in centering the base on the receptacle. In order to make an electrical

connection with the lamp, the receptacle is provided with four cylindrical contact members 10, only two of which are shown. These receive the four lamp contact pins 11 which are electrically connected to the filaments at each end of the lamp tube.

As shown in Fig. 5, the cylindrical contact members 10 are molded into the base 5. Each contact member has a flared end for guiding and receiving the lamp prong which extends into the contact through an opening 12 in the raised projection 8. Each contact member carries a ball contact 13, preferably made of brass, which is biased by means of a spring 14 into engagement with the lamp contact pin. Outward movement of the ball contact is limited by one or more projections 15 struck inwardly from the wall of the contact cylinder. The ball floats freely in the contact cylinder. It compensates for any manufacturing tolerances in the length of the lamp contact pin. Moreover, there is a tendency for the ball to rotate slightly whenever the lamp is mounted on or removed from the holder. This means that a new contact surface is presented to the lamp contact pin each time the lamp is replaced so that a good electrical connection is maintained between the lamp and the holder. An electrical conductor 16 is fastened in any suitable way, as by soldering, to each contact cylinder to provide means for wiring the holder to a fluorescent lamp ballast and starting switch in a manner well understood in the art.

In order to mount the base 5 on the fixture arm 3, the base is formed with an integral extension 17 which fits into a collar 18 to which it is fastened in any suitable manner as by a set screw 19. The collar 18, in turn, is mounted on the fixture arm 3 and is fastened in position by a set screw 20.

Turning now to the construction of the tension support elements and referring to Fig. 4, the support 1 comprises a collar 21 formed as a casting and which is provided with a recess 22 for receiving the fixture arm 3. It is fastened to the arm in any suitable manner, for example, by means of a set screw 23. A clamp 24 of insulating material is pivotally mounted on collar 21 by a pin 25 and is provided with a curved surface 26 for engaging the periphery of the lamp tube. Pin 25 extends through a guide ridge 27 formed on the upper surface of collar 21. When the parts are in assembled position, the guide ridge extends into a recess 28 formed in the clamp 24. In this way, the ridge 27 serves as a guide to insure straightline pivotal movement of the clamp about pin 25. Clamp 24 is biased into engagement with the lamp tube by means of a compression spring 29 seated in recess 28. One end of the spring engages a projection 30 formed in ridge 27 while the other end surrounds projection 31 on clamp 24. The projections serve to hold the spring in position in the recess. In this location, the spring is hidden by the side walls of the recess 28, as will appear from Fig. 2. Although the spring tends to rotate the clamp 24 clockwise, in the showing of Fig. 4, rotation of the clamp is limited by bosses 32 which engage the top surface of collar 21.

One contact receptacle 2 and at least one tension support 1 are mounted on a lamp fixture to form the complete holder. In the form of the invention illustrated, two of the supports 1 are used and each is mounted on a fixture arm 3 of the lamp along with the contact receptacle 2. To mount a circular lamp, the lamp base is

first mounted on the contact receptacle 2 with the lamp pins seated in the cylindrical contact members 10. Then the clamps 24 are pivoted to permit the lamp tube to snap over into position on the curved surfaces 25. Springs 29 force the clamps 24 firmly into engagement with the lamp tube. In addition, the springs tend to pull the lamp base firmly into engagement with the contact receptacle.

It will be apparent that in mounting the lamp, it must be rotated or moved in a slight arc about the base as a center. This means that the lamp contact pins must pivot or move sidewise slightly within the cylindrical contact members 10. The members are made of a sufficient diameter to permit this without damage to the lamp. In other words, the lamp pins do not necessarily make electrical contact with the side walls of the cylindrical contact members 10 but rather are engaged by the floating contact balls 13. The curved surface 6 of the receptacle cooperates with the curved surface of the lamp base 7 to permit relative movement between these two parts as the lamp contact pins pivot in mounting the lamp.

What we claim as new and desire to secure by Letters Patent of the United States, is:

1. A lampholder fixture for a circular tubular lamp comprising, in combination, a base, a plurality of arms extending outwardly from said base and terminating in a circle concentric with the lamp and in a plane parallel to the lamp plane, lamp supporting elements mounted on the end of each of said arms, all of said elements being provided with a similar curved contour having a concave surface shaped to engage a portion of the cross-sectional periphery of the lamp, a lamp contact pin receiving receptacle mounted in the concave surface of one of said elements, and each of the other of said elements comprising a tension support including a recessed clamp member pivotally mounted on the end of its respective arm and spring means in said recess for biasing said clamp member into engagement with the lamp tube.

2. A lampholder for a circular tubular lamp having a tubular base with contact pins extending radially from the base, said lampholder comprising an insulating member having a curved contour with a concave surface, a portion of which is shaped to engage the cross-sectional periphery of the lamp base, a plurality of lamp contact pin receiving cylindrical contact members recessed in said concave surface of said insulating member, contact elements freely floating in said contact members and spring means biasing said contact elements toward said surface.

3. A lampholder for a circular tubular lamp having a tubular base with contact pins extending radially from the base, said lampholder comprising an insulating member having a curved contour with a concave surface, a portion of which is shaped to engage the cross-sectional periphery of the lamp base, a plurality of lamp contact pin receiving cylindrical contact members recessed in said concave surface of said insulating member, ball contacts freely floating in said contact members, spring means biasing said ball contacts toward said concave surface, and means for mounting said insulating member on a support.

4. A lampholder for a circular tubular lamp having a tubular base with contact pins extending radially from the base, said lampholder

comprising an insulating member having a curved contour with a concave surface, a portion of which is shaped to engage the cross-sectional periphery of the lamp base, a plurality of lamp contact pin receiving cylindrical contact members recessed in said concave surface of said insulating member, ball contacts freely floating in said contact members, spring means biasing said ball contacts toward said surface and a recessed base for said insulating member for mounting the same on a lamp fixture arm.

5. A tension support for a circular tubular lamp comprising a clamp member having a curved contour with a concave surface a portion of which is shaped to engage the cross-sectional periphery of the lamp tube, said member having a recess, a supporting member adapted to be mounted on a lamp fixture arm, means pivotally mounting said clamp member on said supporting member and spring means in said recess for biasing said clamp member away from said supporting member about said pivotal mounting in the direction of said concave surface.

6. A tension support for a circular tubular lamp comprising a clamp member having a curved contour with a concave surface a portion of which is shaped to engage the cross-sectional periphery of the lamp tube, said member having a recess, a supporting member adapted to be mounted on a lamp fixture arm and having an abutment thereon adapted to fit into said recess, a pivot pin passing through a wall of said recess and into said abutment for pivotally mounting said clamp member on said supporting member, and spring means in said recess for biasing said clamp member away from said supporting member about said pivot in the direction of said concave surface.

7. A tension support for a circular tubular lamp comprising a clamp member having a curved contour with a concave surface, a portion of which is shaped to engage the cross-sectional periphery of the lamp tube, a supporting member adapted to be mounted on a lamp fixture arm and having a guide member thereon, means pivotally mounting said clamp member on said supporting member, said clamp member having a recess the walls of which are adapted to cooperate with said guide member to restrict movement of the clamp to pivotal movement, and spring means in said recess for biasing said clamp member away from said supporting member about said pivotal mounting in the direction of said concave surface.

8. A tension support for a circular tubular lamp comprising a clamp member having a curved contour with a concave surface, a portion of which is shaped to engage the cross-sectional periphery of the lamp tube, a supporting member adapted to be mounted on a lamp fixture arm and having a guide member thereon, means pivotally mounting said clamp member on said supporting member, said clamp member having a recess the walls of which are adapted to cooperate with said guide member to restrict movement of the clamp to pivotal movement, and a coiled spring in said recess extending between said supporting member and said clamp member for biasing the clamp about said pivotal mounting in the direction of said concave surface.

9. A tension support for a circular tubular lamp comprising a clamp member having a curved contour with a concave surface, a portion of which is shaped to engage the cross-sectional periphery of the lamp tube, an axially recessed supporting collar adapted to be mounted on a lamp fixture arm and having a guide member thereon, means pivotally mounting said clamp member on said supporting collar, said clamp member having a recess, the walls of which are adapted to cooperate with said guide member to restrict movement of the clamp to pivotal movement and a spring in said recess extending between said supporting collar and said clamp member for biasing the clamp about said pivotal mounting in the direction of said concave surface.
